UNITED STATES PATENT OFFICE.

GEORGE K. MALTBY, OF NEW YORK, N. Y.

LAMP.

1,224,189.

Specification of Letters Patent.

Patented May 1, 1917.

Application filed February 16, 1916. Serial No. 78,584.

To all whom it may concern:

Be it known that I, GEORGE K. MALTBY, a citizen of the United States, residing in the city, county, and State of New York, have invented certain new and useful Improvements in Lamps, of which the following is a full and complete disclosure.

My invention relates to an electric lamp, particularly adapted for use in factories, 10 shops, laboratories, etc., where numbers of operators and machines are employed, and where there is a demand for an intense or strong light concentrated on a number of different pieces of work or points.

15 The object of my invention is to provide a lamp for use in such places, which shall be simple and durable, and which will distribute light from a common source to a number of different points and will project 20 the light rays in a downwardly direction and confine them to the particular places where they are desired, so as not to tax the eyes of the operators by light rays projected directly from the source to the eyes.

25 My invention will be readily understood from a description of the preferred embodiment, shown in the drawing accompanying and forming a part of this specification.

In this drawing:

30 Figure 1 is a side elevation of the complete lamp;

Fig. 2 is a horizontal section, taken on the line 2—2 of Fig. 1;

Fig. 3 is a vertical section, taken on the 35 line 3—3 of Fig. 2; and

Figs. 4, 5 and 6 are detail views, showing the means for securing the reflecting tubes to the light chamber.

Referring in detail to these drawings, L 40 designates a base for supporting the lamp, provided with a vertical hollow shaft F, in which the supporting rod E is adapted to slide. The rod E may be secured in any position by the set screw G. A light chamber, formed of the wall sections A¹, A², A³ and A⁴ is mounted at the top of the rod E and contains a source of light in the form 45 of an electric lamp D. The wall sections, at their side edges overlap each other, and 50 are adjustable horizontally by means which I will now describe.

These sections are provided at their bottom with horizontal slots J¹ and at or near their top with horizontal slots J. At their 55 bottom, they are secured to the circular flange M by pins N fixed to the flange M,

and by nuts O mounted on the pins. Likewise, at or near their upper edge they are secured to the annular flange M¹ by pins N¹, which pass through the slots J and J¹ and 60 by nuts O¹. Since the slots J and J¹ are elongated, by loosening the nuts O and O¹, the wall sections may be adjusted horizontally, so as to alter the relative positions of the reflecting tubes B. One of these tubes 65 B is secured to each section and opens into the light chamber at or adjacent the lamp D.

In practice, the tubes B as well as the light chamber may be lined with polished metal, glass, or in any suitable way to reflect light from the lamp D. These reflecting tubes will vary in length, depending upon the particular use to which the device is put. They serve to concentrate the light rays from the single lamp D at a plurality 75 of points and project the light downwardly on the work, so as to minimize the strain on the operator's eyes. In case a general illumination of the building where the lamp is employed is desired, cap C, which is supported by a plurality of rods H, hinged to the cap and supported at their lower ends in sockets, should be raised and supported in the position shown in the drawings. In case no light is desired except that through 80 the reflecting tubes B, by removing the supports H from the sockets, the cap can be lowered and seated directly on the light chamber, so as to cut off all escape of light 85 except through the tubes B.

The lamp described has four reflecting tubes, disposed 90 degrees apart around the light chamber, and is particularly adapted to illuminate four different pieces of work, as sewing machines, for example, when they 90 are arranged in double rows on both sides of a table and equal distances from each other. In case the arrangement of machines is not entirely uniform, the device may still be used by raising or lowering the light chamber and tubes, and if necessary, by adjusting individual tubes in a horizontal direction, so as to concentrate the light from the different tubes directly on the several pieces of work. It is obvious that the number of 100 reflecting tubes on each lamp and their relative location around the light chamber can 105 be varied to suit particular conditions.

What I claim as my invention is:

1. In a device of the kind described, a 110 vertical standard comprising a base and constituting a support, a light chamber

ARTIFICIAL LIGHTING APPARATUS

- mounted thereon and supported in an elevated position thereby, a source of light in said chamber, a plurality of downwardly inclined reflecting tubes opening into said chamber and so disposed as to concentrate and direct the light on a plurality of points around the base of the support. 2. In a device of the kind described, a light chamber, a source of light therein, a plurality of downwardly inclined reflecting tubes opening into said chamber, and means for adjusting the position of said tubes with respect to said light chamber horizontally, for the purpose described. 3. In a device of the kind described, a light chamber, a source of light therein, a plurality of reflector tubes opening into said light chamber and a reflector cover for said chamber adjustable as to height, substantially as described. 4. In a device of the kind described, a circular light chamber having its side walls formed of a plurality of segments adjustable horizontally with respect to the light chamber and to each other, and a reflector tube mounted on each segment and opening into said chamber, substantially as described. 5. In a device of the kind described, a light chamber, a source of light therein, a plurality of reflecting tubes opening into said chamber and a reflector cover for said chamber adjustable as to height, substantially as described. 6. In a device of the kind described, a light chamber above the work to be illuminated, a plurality of downwardly inclined tubes disposed around and opening into said chamber and arranged to concentrate the light rays therefrom on and to illuminate a plurality of separate pieces of work disposed support therefor arranged to support the 30 chamber above the work to be illuminated, a plurality of downwardly inclined tubes disposed around and opening into said chamber and arranged to concentrate the light rays therefrom on and to illuminate a plurality of separate pieces of work disposed 35 below said light chamber. 7. In a device of the kind described, a light chamber, a source of light therein, a support therefor arranged to support the 40 chamber above the work to be illuminated, a plurality of downwardly inclined reflecting tubes disposed around and opening into said chamber and arranged to concentrate the light rays therefrom on and to illuminate a plurality of separate pieces of work disposed 45 below said light chamber, in combination with a reflector disposed above said light chamber and adapted to diffuse rays of light falling thereon for the purposes of 50 general illumination.
